UNITED STATES PATENT OFFICE

HERBERT E. MARKS, OF SEWICKLEY, PENNSYLVANIA, ASSIGNOR TO UNITED STATES GYPSUM COMPANY, OF CHICAGO, ILLINOIS, A CORPORATION OF ILLINOIS

COMBINED FLOOR AND CEILING CONSTRUCTION

Application filed October 10, 1925. Serial No. 61,736.

The object of this invention is to provide a combined monolithic floor and slab ceiling structure, which as a whole may be economically constructed without the use of shoring or false work, and in which certain members entering into the floor structure are arranged for use as supports for ceiling slabs of uniform widths, and a further object is to provide simple and effective means for supporting slab ceilings from a floor.

The invention is illustrated in the accompanying drawings, of which Fig. 1 is a vertical sectional view of the combined floor and ceiling construction, the plane of view being taken transversely of the floor beams, and being indicated by the line I—I, Fig. 2; Fig. 2 a vertical sectional view at right angles to that of Fig. 1; the plane of view being indicated by the line II—II, Fig. 1; Fig. 3 a top plan view of adjacent ceiling slabs and a sectional view of their supporting hangers, the plane of view being indicated by the line III—III, Fig. 1; Fig. 4 an end view of a ceiling slab; Fig. 5 a detail view of one form of hangers for supporting the ceiling slabs; and Fig. 6 a view corresponding to Fig. 5 showing a modification of construction.

The floor constructed according to this invention comprises a plurality of floor beams, which may be and preferably are I-beams or channels, spaced at uniform or varying intervals as may be desired according to the structural requirements and building conditions. Extending transversely of the floor beams and resting upon their tops, there are members, preferably flanged structural sections, which have the double function of supporting the ceiling and of acting primarily as supports for floor forms, although they also may serve to sustain the floor load. Similar members have heretofore been used in floors, but in the present invention these members are of sufficient strength to support the ceiling as well as to perform their function in the floor. Furthermore, as will presently be explained, they are spaced at uniform intervals for a purpose incident to the ceiling construction. For forming the floor without the use of shoring or false work, these mem-

bers support plates on which cementitious material is poured to form a monolithic floor.

The ceiling provided according to this invention consists of pre-formed cementitious slabs of uniform widths arranged below the lower flanges of the floor beams and of sufficient thickness to afford adequate fire-resisting or proofing for them. The slabs are preferably formed of gypsum having inlays of reinforcing material, and are suspended at their ends from the lower ends of compression or thrust resisting hangers which are attached at their upper ends to the supporting members already described. For attaching the lower ends of the hangers to the ends of the ceiling slabs, the reinforcement of the slab is preferably turned upwardly adjacent to the ends of the slabs and projects above their upper faces.

Reference has been made to the uniform spacing of the floor members which extend transversely of the floor beams. By so spacing these members, and by placing the ceiling slabs below the lower edges of the floor beams, it becomes unnecessary to provide ceiling slabs of widths which vary according to the necessary variations in the spacing of floor beams. In other words, except for the fitting of the ceiling slabs adjacent to walls and partitions, all ceiling slabs may be of the same size, thus effecting a substantial saving both in the cost of making and of erecting the slabs.

The invention may be further understood by reference to the embodiment illustrated in the accompanying drawings which show a monolithic floor 1 resting upon the upper flanges of floor beams 2, and a slab ceiling 3 suspended from the floor and lying in a plane below the lower flanges of the floor. Extending transversely of the floor beams, and spaced at uniform widths from each other, there are supporting members 4 which may take the form of small rails as shown in Fig. 2. These supporting members extend continuously over the tops of the floor beams, which cheapens the construction and facilitates its erection by reason of the fact that the supporting members need not be cut to various lengths.

Between supporting members 4, and preferably resting upon their lower flanges, there are plates or boards 5 upon which a body of cementitious material is poured to form a monolithic floor. While these plates may be made of various materials, they are preferably gypsum boards. For supporting the contiguous edges of these plates to prevent them from sagging before the monolithic floor is set, small members may be arranged between the supporting members 4 and rest upon their lower flanges. These small members may take the form of T's 6 such as disclosed in my Patent No. 1,398,079, 10 or they may take the form of boards or strips attached to the adjacent or contiguous sides of plates 5 as disclosed in my Patent No. 1,458,770. Manifestly various other forms may be used, and if plates 5 are in 15 themselves sufficiently rigid to support the cementitious floor material before it has set, such members may be dispensed with entirely.

Upon the tops of plates 5, and embedding the upper portions of transverse members 4, there is a monolithic body 7 of cementitious material, preferably gypsum. This monolithic body may be provided with a reinforcement 8 of welded wire fabric or its equivalent. The floor may be surfaced or finished in any desired manner depending upon requirements. As shown in the drawings sleepers 9 are laid upon the cementitious body 7, and a wooden floor 10 is nailed to 35 them.

The preferred construction of uniform width slabs which form the ceiling is illustrated particularly in Figs. 3 and 4. As there shown each slab 15 comprises a plate-like body of cementitious material, preferably gypsum, having an inlay of welded wire fabric 16, the ends of which are turned upwardly adjacent to the ends of the slab. The arrangement here is such that the outwardly projecting reinforcement includes a wire 17 extending parallel to the upper face of the slab, and short lengths of wire which form posts 18 attached to the transverse wire 17. The slabs herein shown are also disclosed in my co-pending application Serial No. 696,210, and in themselves are claimed in such applications. While it is preferred to use this form of slab, it is manifest that the advantages of the invention may be realized by the use of other specific forms of ceiling slabs. In the embodiment of the invention shown in the drawings the ceiling slabs are arranged below floor 1 and below the lower edges of floor beams 2 in such 50 positions that the adjacent sides of the slabs meet in vertical planes below supporting members 4 in the floor.

Although various forms of hangers may be used for suspending the ends of slabs from supporting members 4, it is preferred to so

construct and arrange the hangers that each forms a support for the corners of a plurality of ceiling slabs. Having reference to the hanger shown in Fig. 5 it comprises a pair of stirrups or clips 20 formed to engage the lower flange of a supporting member 4. The lower ends or legs of these clips are bolted or otherwise attached to the upper ends of a pair of straps 21. As shown particularly in Fig. 3, the corner posts 18 of the projecting reinforcement are engaged by bars 22 having their ends bent around the posts and lying below the transverse projecting wire 17. The central portions of bars 22 are attached to the lower ends of straps 21 by bolts or equivalent members. In this manner the adjacent ends of slabs 15 are bound together by bars 22, and the adjacent slabs are drawn together by the action of straps 21 which tend to draw together at their lower ends due to the weight of the ceiling slabs. By arranging the slabs so that the corners of four of them meet at a common point as shown in Fig. 3, a single composite hanger such as shown in Fig. 5 may be used for supporting all of these corners.

In the form of hanger shown in Fig. 6, a single twisted strap 21a is attached to the lower ends of clips 20, and a bar 22a spans the ends of adjacent slabs, rather than their sides as in Figs. 3 and 5, and engages the corner posts 18 of the projecting reinforcement. At the meeting corners of four ceiling slabs two sets of clips 20 and straps 21a may be used, or a single set of clips 20 and two straps 21a may be used in the manner similar to the hanger construction disclosed in Fig. 5. As shown at the right hand end of Fig. 1 a single twisted strap 21a may be used for supporting the ends of ceiling slabs adjacent to a wall or partition 25. The remainder of the hangers shown in Figs. 1 and 2 are of the form disclosed in Fig. 5 and previously explained.

It has been noted that the upper faces of the ceiling slabs lie below the lower flanges of floor beams 2. The floor beams therefore do not serve to resist upward thrust upon the ceiling slabs when they are plastered from beneath. To resist this upward thrust the hangers are rigid and are so shaped and so connected at their opposite ends that the ceiling slabs do not move upwardly when plaster is applied to them.

In Fig. 2 floor beams 2 are illustrated as being attached at their ends to a floor girder 26 which does not lie in a partition or wall, and which, being of greater depth than the floor beams, extends materially below their lower flanges. For supporting the ends of ceiling slabs adjacent to a floor girder, and also for fireproofing the girder, a trough 27 formed of cementitious material encases the lower portion of the floor beam to the required depth and forms at its upper edges

supports for the ends of adjacent ceiling slabs. These troughs are preferably provided with reinforcing wires or equivalent members 28 which project upwardly beyond the upper edges of the trough a sufficient distance for use in attaching the trough to the upper flange of the floor girder by bending the wires around the girder as illustrated.

As shown in Fig. 1, the ceiling slabs are arranged below the lower flanges of the floor beams. The space between the upper faces of the slabs and the lower faces of the floor beams is sufficient to accommodate the projecting ends of the slab reinforcement. By so arranging the ceiling slabs they may terminate at any point regardless of the spacing of the floor beams. At the left of Fig. 1 they are shown as terminating immediately below floor beam 2, while the ceiling slab below the right hand floor beam terminates at opposite sides of the beam. This arrangement, coupled with the uniform spacing of supporting members 4, makes it possible to use slabs of uniform width, and results in a very substantial economy in the cost of materials and in the erection of the combined floor and ceiling.

According to the provisions of the patent statutes I have explained the principle and operation of my invention, and have illustrated and described what I now consider to represent its best embodiment. However, I desire to have it understood that, within the scope of the appended claims, the invention may be practiced by other forms of construction than that particularly illustrated and described.

I claim:

1. A combined floor and ceiling structure comprising spaced floor beams, combined floor-form and ceiling-supporting members resting independently of each other upon the tops of and extending transversely of the floor beams and spaced at uniform intervals, floor-form plates supported by said members, a monolithic floor formed on said plates, hangers separately engaging and independently extending downwardly from said uniformly spaced members and arranged at a plurality of intervals between said floor beams, and pre-formed cementitious fireproofing ceiling slabs of uniform width attached at their ends directly to said hangers and lying in a plane below the lower edges of said floor beams.

2. A combined floor and ceiling structure comprising spaced floor beams, combined floor-form and ceiling-supporting members resting independently of each other upon the tops of and extending continuously over and transversely of the floor beams and spaced at uniform intervals, floor-form plates supported by said members, a monolithic floor formed on said plates, hangers separately engaging and independently extending downwardly from said uniformly spaced members

and arranged at a plurality of intervals between said floor beams, and pre-formed cementitious fireproofing ceiling slabs of uniform width attached at their lower ends directly to said hangers and lying in a plane below the lower edges of said floor beams.

3. A combined floor and ceiling structure comprising spaced floor beams, combined floor-form and ceiling-supporting members resting independently of each other upon the tops of and extending transversely of the floor beams and spaced at uniform intervals, floor-form plates supported by said members, a monolithic floor formed on said plates, thrust-resisting hangers separately engaging and independently extending downwardly from said uniformly spaced members and arranged at a plurality of intervals between said floor beams, and pre-formed cementitious ceiling slabs of uniform width having hanger-engaging members at their ends projecting above their upper faces, said slabs lying in a plane below the lower edges of said floor beams and having their hanger-engaging members directly attached to the lower ends of said hangers.

4. A combined floor and ceiling structure comprising spaced floor beams, combined floor-form and ceiling-supporting members resting independently of each other upon the tops of and extending transversely of the floor beams and spaced at uniform intervals, floor-form plates supported by said members, a monolithic floor formed on said plates, thrust-resisting hangers separately engaging and independently extending downwardly from said uniformly spaced members and arranged at a plurality of intervals between said floor beams, and pre-formed cementitious ceiling slabs of uniform width lying in a plane below the lower edges of said floor beams and provided at their corners with hanger-engaging members projecting upwardly from the upper faces of the slabs, each of said hangers being directly attached to said hanger-engaging members of a plurality of said ceiling slabs.

5. A combined floor and ceiling structure comprising spaced floor beams, combined floor-form and ceiling-supporting members resting independently of each other upon the tops of and extending continuously over and transversely of the floor beams and spaced at uniform intervals, floor-formed plates supported by said members, a monolithic floor formed on said plates, thrust-resisting hangers separately engaging and independently extending downwardly from said uniformly spaced members and arranged at a plurality of intervals between said floor beams, and preformed cementitious ceiling slabs of uniform width lying in a plane below the lower edges of said floor beams and having their sides in vertical alignment with said supporting members of the floor, said

slabs having hanger-engaging members embedded in them and extending upwardly at the corners of the slabs above the plane of the upper faces of the slabs, and means for attaching each hanger directly to the floor-engaging members of a plurality of said slabs.

In testimony whereof, I sign my name.
HERBERT E. MARKS.
